METHOD FOR PREVENTING THE LOSS OF
DRILLING FLUID DURING THE DRILLING
OF WELLS

James F. Larkin, Oklahoma City, Okla.; Katharine Larkin Angus, administratrix of James Francis Larkin, deceased

Application May 8, 1940, Serial No. 333,969

2 Claims. (Cl. 166—22)

This invention relates to a method of preventing the escape of drilling fluid into porous underground strata and particularly into underground crevices and fissures during the drilling of wells.

At the present time when loss of the drilling fluid occurs, cotton seed hulls, oat chaff, cut straw, or any of a number of other fibrous materials are introduced into the drilling fluid, and circulation of the drilling fluid under pressure is continued until a sufficient amount of the fibrous material used lodges in the particular formation or formations into which the fluid is escaping, and by its bulk completely fills up the crevices, fissures, pores, etc., of the formation or formations. This method is costly, however, because a continuous flow of liquid is necessary to carry the fibrous material into the cracks and fissures, and a continuous flow of liquid means the loss of an enormous quantity of drilling fluid before the fibrous material is deposited in sufficient quantity to completely fill the cracks and crevices. This loss of the drilling fluid, as stated, is very expensive, hundreds of tons sometimes being lost in a single well.

It is the chief object of the present invention to provide a method and means for stopping up or plugging the cracks, crevices, fissures, etc., in underground formations at their mouths, eliminating the necessity of completely filling the remote recesses of those cracks, crevices, etc., with a consequent reduction in the amount of fluid ordinarily lost during the stopping up or sealing of such cracks, etc., and a similar reduction in the amount of sealing or plugging material required. Like characters of reference designate like parts in the figure. One embodiment is shown in the figure; the figure is a vertical sectional view through a portion of the earth depicting the mechanism for carrying out the method operatively installed therein.

The invention contemplates the use of small pieces of sponge rubber, in place of any of the fibrous materials above mentioned, to stop up the cracks, crevices, and fissures at or near their respective mouths. Sponge rubber, naturally, may be comparatively easily compressed to approximately one-fourth of its normal volume without in any way effecting its ability to resume its normal size after the pressure is removed. It is an ideal material for this purpose because when it is compressed into the mouths of cracks and crevices, its inherent ability to expand holds it firmly in position even after the original compressing force is completely removed.

According to the invention, when escape of the mud and consequent loss of circulation during

drilling is noticed, the mud pump, which is used to circulate the mud in the hole during the drilling operation, is shut off. Naturally, the mud level lowers to a point adjacent the lowermost cracks and crevices into which the mud is escaping. The drill stem may then be removed and a quantity of small pieces of sponge rubber may be introduced into the well.

By volume displacement, the sponge rubber causes the level of the drilling fluid standing in the hole to rise. Ordinarily this fluid level rise will be sufficient to start the fluid flowing out through most all of the cracks and crevices, and this outflow carries the pieces of sponge rubber into the mouths of the cracks and crevices. In view of the fact that there is no forced circulation of fluid at this time, and hence no fluid pressure to rapidly force the fluid into the cracks and crevices, the fluid flow is slow, and the small sponge rubber pieces move at approximately the same speed as the fluid which carries them. During this slow fluid flow, the small sponge rubber pieces, by their contact with the sides of the mouth of the various cracks and crevices, create a "dam" or "log jamb" across the mouths of the cracks, much as a "log jamb" is formed in a flowing river. This accumulation of sponge rubber pieces continues until the entire mouth of each crack and crevice is plugged. As the mouth of each crack is plugged, the fluid rises above that point, and the head pressure created serves to compress and compact the various pieces of sponge rubber more tightly into the mouth of the submerged crack or opening. The drill stem may then be replaced, the mud pumps started, and the fluid level in the hole raised above the plugged cracks and fissures to test whether or not the leaks in the formation have been sealed by the sponge rubber. If the leakage has been stopped, drilling fluid circulation and drilling may then be resumed and the head pressure of the column of fluid in the hole further compresses the individual pieces of sponge rubber and forces each conglomerate plug more firmly into its particular crack or crevice. Thus when the pressure is again removed from the drilling fluid, the expansion of the individual pieces attempting to resume their natural sizes and shapes holds them firmly within the mouths of the various crevices. Such is not possible with fibrous materials, for they have comparatively little inherent resiliency.

Should the test show that mud is still escaping from the hole, the pump pressure is again shut off and additional pieces of the sponge rubber are incorporated in the drilling fluid and introduced

into the well through the drill stem, as illustrated in the drawing, in a manner similar to the manner in which cotton seed hulls or any other fibrous material is now introduced into wells, as previously mentioned. The pumping of this sponge rubber impregnated drilling fluid into the well carries additional quantities of the spongy material to the mouths of the leaking cracks and crevices, but the actual loss of drilling fluid is small because the mouths of the cracks and crevices are already partially plugged.

When a sufficient quantity of the material has accumulated to completely plug the mouths of the lowermost cracks in the hole, the fluid level rises and carries additional sponge rubber pieces into the mouths of the cracks and crevices located at a higher elevation. Also as the fluid rises above certain plugged cracks, the pressure on the elastic spongy material plugging those cracks increases, thus compressing the material and making room for additional pieces of sponge rubber in the mouths of those particular cracks. The sponge rubber pieces are thus wedged tightly into the mouths of the cracks, much as a cork is used to plug the mouth of a bottle.

After sufficient time has elapsed, the formation is again tested for leakage, as previously described, and if it is found that mud still escapes, the pump is promptly shut off to permit an additional quantity of the sponge rubber pieces to be similarly introduced into the drilling fluid. When such a test shows that the leakage has been stopped, drilling and the attendant circulation of plain drilling fluid is resumed, and the pressure of the mud column outside the drill stem compresses and forces the various pieces of sponge rubber more tightly into the mouths of the plugged cracks and crevices of the porous formation. Naturally when the pump pressure is removed, the various pieces of sponge rubber compressed into the mouths of the cracks and crevices tend to expand, which tendency causes a firm contact against the sides of the cracks, and holds the conglomerate plugs in their respective positions, as previously mentioned.

It should be explained that it is not absolutely necessary to withdraw the drill stem when originally introducing the sponge rubber into the hole. If preferred, all the sponge rubber may be introduced through the drill stem, as explained in the latter part of the above description.

From the above description it will be seen that the use of my method produces three very important results:

1. It generally reduces the amount of drilling fluid lost during the treatment of a well to seal or plug its cracks and crevices.

2. It greatly reduces the quantity of material required to prevent further loss of drilling fluid because the material and method used plugs the mouths of the respective cracks and crevices instead of completely filling their remotest recesses.

3. The seal or plug formed is not subject to deterioration during the continued drilling of the well, nor to destruction due to the removal and reinsertion of the drill bit and stem from the well, nor to disintegration when the fluid pressure in the well drops to zero during bailing out of the drilling fluid.

In the drawing the numeral 6 designates a drill stem as a whole, numeral 7 designates a bit on the lower end of the stem; a circulation duct through the bit 7 is indicated by the dotted lines 8; the fluid level to which the mud settles in the well 9, after the pump pressure has been shut off, is indicated by the numeral 10, while the dotted line 11 indicates the approximate height to which the mud level rises due to the expansion of the various small pieces 12 of sponge rubber. The various cracks and crevices of the porous formation 5 are designated by the numerals 13 and 14.

Having described the invention, what is claimed is:

1. The method of plugging cracks and fissures in underground formations to prevent loss of fluid from a well drilled into the formation which comprises the steps of: introducing a quantity of high viscosity mud into the well from a point near its bottom; introducing a quantity of small pieces of sponge rubber into the mud in the well; raising the liquid level of the mud in the well by fluid pressure applied at the original point of introduction, to a point where escape of mud is noticeable; removing the fluid pressure to allow the sponge rubber particles to expand, and to be carried by the consequent further rise of the fluid level of the mud into the cracks and crevices; and then flowing the mud under pressure upward through the well to force the sponge rubber pieces further into said cracks and crevices.

2. The method of plugging cracks and fissures in an underground formation penetrated by a well bore which comprises the steps of filling the well bore with a liquid up to a point near the level of the lowermost cracks to be plugged, introducing a quantity of small pieces of sponge rubber into the well bore, and applying fluid pressure to compress and force said sponge rubber pieces into the mouths of said cracks, where they are lodged by their own expansion when the fluid pressure is removed.
